UNITED STATES PATENT OFFICE.

JAMES M. CREWS, OF ARLINGTON, TENNESSEE.

COTTON-SCRAPER.

SPECIFICATION forming part of Letters Patent No. 424,962, dated April 8, 1890.

Application filed January 22, 1890. Serial No. 337,678. (No model.)

To all whom it may concern:

Be it known that I, JAMES M. CREWS, a citizen of the United States, residing at Arlington, in the county of Shelby and State of Tennessee, have invented a new and useful Cotton-Scraper, of which the following is a specification.

This invention relates to cotton-scrapers; and it has for its object to construct a device 10 of this class which shall be simple and inexpensive, durable, and efficient in operation, and which may be readily adjusted or regulated so as to work in ridges or beds of any width.

15 The invention consists in the improved construction, arrangement, and combination of parts, which will be hereinafter described, and particularly pointed out in the claims.

In the drawings hereto annexed, Figure 1 20 is a perspective view of my improved cotton-scraper. Fig. 2 is a plan view of the same. Fig. 3 is a transverse sectional view taken on the line *x x* of Fig. 2, and Fig. 4 is a transverse sectional view taken on the line *y y* in 25 Fig. 2.

Like numerals of reference indicate like parts in all the figures.

1 designates a beam, which is of the construction of an ordinary plow-beam and which 30 is provided with handles 2 2, which are connected with the rear end of said beam by means of inclined braces 3 3.

4 designates an iron plate having forwardly-converging side edges 5 5. This plate is secured to the under side of the plow-beam 1 by means of bolts 6 6, the front one of which is located to the left of a central longitudinal line, while the rear bolt is located to the right of such a line, thus placing the beam in a laterally-inclined position, which enables the team to walk on the left side of the row of plants which is being operated upon. Near the edges of the plate 4, at the front and rear ends of the same, are formed longitudinal 45 slots 7 and 8, in which are hinged metallic straps 9 and 10, the latter of which, being hinged in the rear slots 8, are somewhat longer than the front straps 9, so that the front ends of the scraper-blades are elevated. Suitably 50 secured to the lower ends of said straps are the scraper-blades 11 and 12, the rear ends of which are even with each other, while the

front end of the blade 11 is extended some distance in front of the blade 12. The front edges of the blades are slightly curved outwardly, as shown at 13, and the lower edges of the blade are likewise curved outwardly, as shown at 14, for the purpose of throwing the dirt outwardly from the plants. The blades 11 and 12 are connected near their front ends 55 by a transverse bolt 15, upon which is coiled a spring 16, by means of which the said blades are spaced apart. The rear straps 10 are connected by a coiled spring 17, inclosing an iron rod 18, which is to so adjust the blades or 60 scrapers that they will adapt themselves to any size bed or ridge upon which the cotton is planted.

From the foregoing description, taken in connection with the drawings hereto annexed, the operation and advantages of my invention will be readily understood.

The draft is attached to the front end of the beam and the machine is dragged over the field, straddling the rows of plants and stirring and scraping the soil in the usual well-known manner.

The construction of the device is exceedingly simple and inexpensive, and it may be operated very easily and with most satisfactory results.

Having thus described my invention, I claim and desire to secure by Letters Patent—

1. In a cotton-scraper, the combination of a beam, a plate secured horizontally to the under side of said beam and having longitudinal slots near its edges, the straps hinged in the said slots, and the blades or scrapers secured to the lower ends of said straps, substantially as set forth. 85

2. In a cotton-scraper, the combination of a beam, a plate secured horizontally to the under side of said beam and having forwardly-converging side edges and slots near the front and rear ends of the said edges, the straps 95 hinged in the said edges, the blades or scrapers secured to the lower ends of said straps, the adjusting-bolt connecting the front ends of said blades or scrapers, and a spacing-spring coiled upon the said bolt, substantially 100 as set forth.

3. In a cotton-scraper, the combination of a horizontal plate having forwardly-converging side edges and longitudinal slots near the

- front and rear ends of said edges, a beam secured upon the upper side of said plate in a laterally-inclined position, the straps hinged in the slots of said plate, the blades or scrapers secured to the lower ends of said straps, the transverse bolt connecting the front ends of said blades and having a coiled spacing-spring, a coiled spring connecting the rear hinge-straps, and a spacing-rod inclosed by 10 said spring, substantially as set forth.
4. In a cotton-scraper, the combination of the beam, the slotted supporting-plate, the hinge-straps, the blades secured to the latter and having outwardly-curved front and lower 15 edges, and the bolts and springs connecting

and spacing the said blades or scrapers, substantially as and for the purpose set forth.

5. In a cotton-scraper, the beam, in combination with the horizontal plate secured to the beam, the straps hinged to the plate, the 20 blades or scrapers secured to the straps, and the adjusting-bolt and spacing-spring, as set forth.

In testimony that I claim the foregoing as my own I have hereto affixed my signature in 25 presence of two witnesses.

JAMES M. CREWS.
